WEDGE FOR TOOL HANDLES

Henry La France, Rumford, Maine

Application December 14, 1945, Serial No. 635,022

1 Claim. (Cl. 306—33)

1

This invention relates to wedges for tool handles and particularly to wedges for axe handles, the principal object being to provide a device of this class that may be easily and quickly inserted into the axe handle and likewise quickly removed therefrom when replacement of the said handle becomes necessary.

Another object is to construct a wedge which has the above advantages yet is simple in design and inexpensive to manufacture.

In the drawing—

Figure 1 is a perspective view of an axe head with the handle inserted through the eye therein and with my invention shown in place in the said handle.

Figure 2 is an enlarged cross sectional view taken at **2—2** in Figure 1.

Figure 3 is a similar view taken at **3—3** in Figure 1.

Figure 4 is a full scale perspective of my device in open position.

At **1** is indicated the usual type of axe head which has the opening or eye for insertion of the handle **2**. With an ordinary hand saw or other suitable tool, a tapering slot, such as **3**, is cut in the end of the handle which is to fit into the eye.

The wedge is made of sheet metal of a suitable thickness and is stamped in the shape of a pair of semi-circular discs which are joined at the center of their arcuate sides and then bent at their joined edges into parallel alignment thus forming a split semi-circular disc as shown at **4**. Aligned openings **5** in the disc pieces, receive a rivet **6** which forms a hinge pin for the wedge-shaped member **7**. The member **7** is preferably made of cast or drop forge steel since it must be driven into place when in use, by the blows of a hammer. At the end opposite the hinge, the member **7** has formed integral therewith an eyelet or ring indicated at **8**.

In employing my device, the slot **3** is first made in the axe handle as above described. The slotted end of the handle is then inserted in the usual manner through the eye in the axe head and the disc portion **4** of my device pressed into the slot, the point at which the discs are united entering first. When the disc portion is entirely within the slot, the wedge member **7** is swung upon its hinge pin until its thinnest edge has entered between the exposed edges of the disc

2

members. Blows of a hammer upon the outer or thickest edge of the member **7** will then force it into place between the discs, thus locking the handle within the axe head.

As frequently happens with lumbermen or wood choppers, an axe handle is broken while in use at a location where no facilities are at hand for quickly and easily removing the broken handle and replacing it with a new one. With the use of my device the operation becomes very simple and considerable time and effort are thereby saved.

To remove the handle, any suitable tool such as an ordinary screw driver may be employed.

The tool is merely inserted through the eyelet **8** and, used as a lever, the member **7** is easily extracted. By grasping the member **7**, the disc portion of the device is quickly removed from the slot in the handle and the said handle may then be readily withdrawn from the eye in the axe head.

Having now described my invention what I claim is:

In a wedge for securing axe handles and the like in axe heads and the like, the combination, which comprises a split substantially semi-circular wedge forming two segments integrally connected at an intermediate point of their curved edges, an inner wedge element adapted for insertion with a rotary movement between said segments, said inner wedge element having an ear extending at one end and positioned adjacent the thick side forming the back thereof, and an eye extending from the back at the opposite end thereof, and a pin pivotally mounting said inner wedge element through the extending ear thereof to one corner of said segment positioning said inner wedge for insertion between the segments with a rotary movement.

40 **HENRY LA FRANCE.**
